UNITED STATES PATENT OFFICE

2,513,536

ALL ANGLE OF IMPACT INERTIA FUSE

Cary L. Wellington, Long Island City, N. Y., as
signor to the United States of America as repre-
sented by the Secretary of War

Application January 3, 1947, Serial No. 720,039

2 Claims. (Cl. 102—76)

1. My invention relates to fuses for military explosives and while particularly applicable to projectiles such as shells, bombs, grenades, rockets and the like, is also applicable to mines, booby traps and other such non-projected explosives; or, in a non-military sense as an anti-tamper device which will sound an alarm when disturbed.

With the foregoing in view, an object of my invention is to provide an improved fuse for military use.

A further object is to provide an improved anti-tamper device.

A further object is to provide an improved arming means for a military fuse.

A further object is to provide a novel fuse comprising means for holding the fuse in an unarmed condition, time actuated means for so arming the fuse that it is actuated upon any slight disturbance or upon impact.

Other objects and advantages reside in the particular structure of my invention, combination and arrangement of the several parts and in the particular mode of operation, all of which will be readily apparent to those skilled in the art upon reference to the drawing and the specification wherein the invention is shown, described and claimed.

In the drawing:

Figure 1 is a longitudinal section through a mechanical embodiment of the invention, the parts being shown in the unarmed position;

Figure 2 is a similar view of the form of the invention of Figure 1, but showing the parts in the armed position;

Figure 3 is a transverse section taken on a plane corresponding substantially to that of the line 3—3 of Figure 1; and

Figure 4 is a fragmentary longitudinal section, diagrammatically showing an electrical embodiment of the fuse, the parts being shown in the armed position.

In the drawing, wherein like reference characters have been used throughout to designate like parts, 9 is a fuse casing having a driven, rotatable shaft 23 journaled in the outer end of the casing and extending inwardly and axially thereof. A pinion 11 on the outer end of the shaft 23 is connected to any suitable driving means (not shown) for rotating said shaft to arm the fuse in a manner to be apparent hereinafter. The shaft 23 has an outer threaded portion 23a just inside the outer end wall of the casing and a second threaded portion 23b on the free inner end of the shaft. The portion of the shaft intermediate the threaded portions 23a and 23b is

unthreaded and of a slightly smaller diameter than the threaded portions. An outer nut 30 is threaded on the portion 23a of the shaft and an inner nut or latch 35 is threaded on the inner threaded portion 23b. Any suitable means, such as keys and keyways prevent the nuts from rotating as the shaft 23 is rotated, but permits the nuts to travel axially along the shaft in a direction inwardly of the fuse when the shaft is rotated in one direction. The outer nut 30 has its inner end formed to provide a convex cam surface 26. The opposed or outer end of the inner nut 35 is also formed to provide a convex cam surface 34.

15. A cylindrical weight 32 surrounds the shaft 23 and is formed with concave cam surfaces 31, 33 on its outer and inner end surfaces respectively. The weight 32 is gripped normally between the opposed convex cam surfaces of the nuts 30 and 35. When the fuse is unarmed (Figure 1), the weight 32 is rigidly held in spaced concentric relation to the shaft 23.

The far end of the nut 35, hereafter called the latch, is axially bored and slidably receives the firing pin cup 36 and firing pin spring 37. A firing pin 50 is formed on the free end of the cup 36. The inner end of the latch or nut 35 is formed with radial holes 38, each of which loosely receives a ball 39. As shown in Figure 1, outward movement of the balls 39 is prevented by their engagement with the inner wall surface 41a of a sleeve 41. The balls 39 extend slightly into the axial bore of the latch 35 and normally engage the annular cam surface 40 of the cup to hold the firing pin cocked and to prevent axial inward movement thereof. The sleeve 41, inwardly of the latch receiving portion 41a, is enlarged to form a chamber 44 which forms an annular shoulder 42, with said portion 41a. The other end of the chamber 44 is closed by an end wall 55 which mounts the primer 51 centrally thereof and beyond which is located the booster charge 52.

In operation, when the shaft 23 is rotated in an arming direction, the nut 30 and nut-latch 35 are moved simultaneously axially inwardly of the fuse until they clear the threaded portions 23a and 23b of shaft 23 and reach the Figure 2 position. At this point, the latch 35 has advanced along the recess 41a and the length of such portion is so related to the threads on portions 23a and 23b that when the nuts clear such threaded portions, and axially movement of the nuts cease, the balls 39 are substantially bisected by the annular shoulder 42. Further rotation of the shaft 23 will not advance the nuts and further

advance of the nut-latch 35 is prevented by a coil spring 43 which is interposed between the inner end of the latch 35 and the floor 55 of the chamber 44. The weight 32 is now held in spaced concentric relation to the shaft 23 solely by the pressure of the spring 43. It is obvious that this is an unstable arrangement and/or hair trigger setting, that upon any sudden shock, such as the impact of the fuse with the ground in the case of a projectile, that the weight 32 will be dislodged and its cam surfaces will cooperate with the complementary cam surfaces of the nut 30 and latch 35 to move the latter axially inwardly of the fuse against the pressure of the spring 43. This moves the balls past the shoulder 42 and they are forced radially outward into the chamber 44 by the cam surface 40 of the firing pin cup 36. The firing pin spring now is free to force the firing pin inwardly into the primer 51 to detonate the same and the booster 52.

The strength of the spring 43 may be varied from a substantially strong one if less sensitivity is desired to a comparatively weak one for great sensitivity. The latter effect is particularly desirable in the case of mines, booby traps, and other non-projected explosive devices, as well as in the case of non-military anti-tamper devices, and provides an effective anti-lifting device, yet the arming feature makes the device perfectly safe until it is armed. It is obvious that in the case of dropped or projected missiles, that the inertia of the weight 32, together with its concavo-convex cam engagement with the nut and latch, will operate to dislodge the weight and fire the charge irrespective of the angle of impact of the missile.

Figure 4 shows a modification wherein the fuse is detonated by electricity instead of mechanically. The arming operation and parts are substantially the same except that the primer 151 is wired for electrical detonation, and the firing pin cup 136 actuates a switch 152 when it is released, whereby to close the circuit to the primer. This form of the invention has been shown diagrammatically because it is obvious that a multiple of circuit closing means are adaptable to my invention.

The electrical form shown in Figure 4 is particularly adaptable to a non-military anti-tamper device as it is obvious that it is only necessary to substitute an electrically operated alarm for the detonator and to leave the device in the armed position. At the same time, the mechanical form of Figures 1, 2 and 3 may also be used as an anti-tamper alarm by substituting a mechanical alarm for the detonator.

While I have shown and described what are now thought to be the preferred forms of my invention, it is obvious that the same is susceptible of other expressions and embodiments. Consequently, I do not limit myself to the structures hereinbefore shown and specified, except as hereinafter claimed.

I claim:

1. An arming device for a fuse, comprising a shaft, means for rotating said shaft, spaced inner and outer threaded portions on said shaft, two nuts, one of said nuts being threaded on each of said threaded portions, means for preventing rotation of said nuts as said shaft rotates whereby

said nuts travel axially on said shaft and inwardly of the fuse as the shaft rotates, opposed convex cam surfaces on said nuts, a cylindrical weight concentric with said shaft, the inner periphery of said weight being spaced from said shaft, concave cam surfaces on the ends of said weight and engaging said convex cam surfaces on said nuts to maintain said weight in spaced concentric relation to said shaft, a spring bearing against the inner surface of said inner nut, a hollow sleeve slidably mounting said inner nut and including an enlarged chamber forming an annular shoulder with said portion of said sleeve mounting said inner nut, said inner nut being formed with an axial bore in the inner end thereof, a spring loaded firing pin in said bore and including an annular cam shoulder on the inner end thereof, radial apertures through said bore portion of said inner nut, a ball mounted in each aperture and held therein by the wall of said sleeve and the cam shoulder of said firing pin, said balls comprising means to prevent the actuation of said pin, said balls being adapted to be positioned on said shoulder when said nuts clear said threaded portions of said shaft whereby a shock will actuate said weight to force said second nut inwardly and permit said firing pin to force said balls into said end cavity of said sleeve to free said firing pin.

2. In a fuse which comprises an inertia actuated weight for detonating the fuse, means for arming the fuse comprising a shaft, spaced and identical threaded portions on said shaft, means for rotating said shaft in one direction, a nut threaded on each of said threaded portions, said nuts normally gripping said weight therebetween to prevent inertia actuation thereof, said nuts being adapted to travel axially of said shaft with said weight as said shaft is rotated until they clear said threaded portions whereby to arm said fuse, and spring means thereafter forcing said nuts into gripping engagement with said weight, said weight being cylindrical and being concentrically spaced from said shaft, there being complementary cam surfaces on said weight and said nuts, a spring loaded actuating pin, a latch engaging said pin to prevent actuation thereof, and means responsive to movement of said weight against said nut cam surfaces and against the action of said first-named spring to release said latch for operation of said actuating pin by its spring.

CARY L. WELLINGTON.
